UNITED STATES PATENT OFFICE.

EMIL E. NOVOTNY, OF RIVERSIDE, ILLINOIS, ASSIGNOR TO J. STOGDELL STOKES, OF MOORESTOWN, NEW JERSEY.

CASTING-BOX.

1,357,342.

Specification of Letters Patent.

Patented Nov. 2, 1920.

Application filed May 29, 1917. Serial No. 171,667.

To all whom it may concern:

Be it known that I, EMIL E. NOVOTNY, a citizen of the United States, residing at Riverside, in the county of Cook and State 5 of Illinois, have invented new and useful Improvements in Casting-Boxes, of which the following is a specification.

This invention relates to casting boxes adapted particularly for use in the manufacture of cast or molded printing plates.

In the casting or molding of printing plates from plastic material, it is of course desirable to employ pressure in order to insure that the impression face of the resulting plate will present printing and non-printing portions of a requisite depth, sharpness and detail, and this necessitates the confinement of the plastic material during the molding or pressing operation, as it 10 is essential that the spread or lateral flow of the plastic composition be reduced to a minimum to obtain an accurate replica of the matrix. Furthermore it is desirable in the manufacture of plastic plates that the latter, at the completion of the molding operation in the casting box, should embody finished details of structure, such as trimmed edges, plain or undercut bevels and the like.

In some instances it may also be found advantageous to mold the plate with the back face, or other non-printing portion thereof, equipped with projections, bosses, or other designations or indications for obtaining the proper registration or location of 15 the printing plate in a predetermined position on the printing press.

In carrying out my invention it is my purpose to provide a casting box wherein a matrix may be securely held or clamped in 20 a predetermined position during the molding operation for the purpose of making a plate which may be accurately and instantly spotted or located in a predetermined position of registration on the plate support of 25 the press.

Furthermore I propose to provide a casting box wherein the plastic material from which the plate is made will be confined against undue or excessive side flow during 30 the molding operation, so that the pressure exerted upon such material will cause the latter to flow in lines parallel with the direction of pressure, thus forcing the ma-

terial into the minutest depression of the matrix and thereby insuring the reproduction of the details of the matrix face. 55

Another object of my invention is the provision of a casting box which will possess a relatively great capacity in that a number of printing plates of various sizes may 60 be simultaneously molded therein, with each printing plate structurally formed for a particular press and for the predetermined position or location it is to occupy on such press. 65

I also aim to provide a casting box which is capable of considerable flexibility of operation, in the sense that it may be adjusted or built up to accommodate matrices and plates of different sizes or a number of 70 matrices and plates, the casting box being so constructed that the possibility of any matrix being embedded in or embraced at its marginal edge by the plastic material from which the plate is made is avoided. 75

With the above recited objects and others of a similar nature in view, my invention consists in the construction, combination and arrangement of parts set forth in and falling within the scope of the appended 80 claims.

In the accompanying drawings:

Figure 1 is a top plan view of the bottom section of one form of casting box embodying my invention and showing four matrices 85 set up therein.

Fig. 2 is a longitudinal sectional view taken on the line 2—2— of Fig. 1.

Fig. 3 is a perspective view of the built-up bed section of the casting box shown in 90 Figs. 1 and 2, a portion of the clamping means being omitted to show the manner of fastening the matrix on the bed.

Fig. 4 is a detailed perspective view of one of the sections of the bed shown in Fig. 95 3, and also illustrating the positioning of one of the clamp sections thereto, the clamp in this instance having an external or outside backing strip placed thereagainst.

Fig. 5 is a vertical cross-sectional view 100 taken on the line 5—5 of Fig. 1 but also showing a portion of a core plate, partly in section and partly in elevation, positioned above the matrix clamp.

Fig. 6 is a transverse sectional view taken 105 on the line 6—6 of Fig. 1 and also illustrat-

ing a portion of the core plate located in adjusted position thereto.

Fig. 7 is a view partly in section and partly in elevation showing the operation of molding plates in a casting box in a press.

Fig. 8 is a perspective view of a modified form of built-up casting-box bed, and illustrating a clamping member as equipped with means for insuring proper positioning of the matrix on the bed.

Fig. 9 is a view partly in section and partly in elevation of a casting box in a press and illustrating the manner of casting the plate with a backing of wood or the like applied to the plastic plate material.

Fig. 10 is a perspective view of a modified form of casting box bed.

Fig. 11 is a cross sectional view taken on the line 11—11 of Fig. 10.

Fig. 12 is a plan view of another modified form of casting box for casting a flat plate and showing an adjustable core plate.

Fig. 13 is an end view of the casting box shown in Fig. 12.

Fig. 14 is a perspective view of a casting box for molding a curved plate, a corner of the box being cut away to show the interior arrangement of the parts.

Referring particularly to Fig. 1 of the drawings, the numeral 1 indicates a frame, which in the present instance is shown in rectangular form and is preferably composed of any suitable metal, this frame forming a part of the bottom section of the casting box, such bottom section also including the bed B upon which the matrix is intended to rest. The bed B is preferably made up of a series of assembled blocks 2, these blocks being of various sizes and shapes, preferably multiples of points and picas according to ordinary printers' measurement. From this it is to be understood that by means of these blocks 2, a bed of any suitable size or area may be built up to accommodate matrices of any preferred form or size, four of such matrices being indicated by the letter M in Fig. 1. These blocks are preferably made of metal with the sides thereof accurately machined and ground so as to form a close, tight fit at all contacting faces. For the purpose of holding the matrices rigid and stationary on the bed B of the box I employ a suitable number of side clamping members C and corner clamping members D, best shown in Fig. 3. Each of the side clamping members C comprises a vertical wall 5 having a downwardly and inwardly projecting beveled or hook-like flange 6 at the upper end thereof. Likewise each of the corner clamping members D comprises an angular vertical wall 7 with an angular hook-like flange 8 projecting downward and inward from the top edge thereof. The under or bottom face of each of these flanges 6 and 8 is substantially

horizontal as shown at 9 so as to extend approximately parallel with the top face of the bed B when clamping a matrix against the bed as clearly shown in Fig. 3. Certain of the clamping members, preferably those 70 near one corner of the bed, are formed along their upper edges with small, spaced, preferably semi-circular lugs 10 which are adapted to seat in similarly spaced sockets 11 formed in the under faces of a core plate E 75 of the casting box as shown in Fig. 7. I might state here that, as shown in Figs. 5 and 7, this core plate which is positioned above the matrix, is provided on its under face with a field of these sockets, indicated 80 by the numeral 11, arranged in rows spaced equi-distance apart.

The purpose of these sockets 11 on the core plate as shown in Fig. 7, is to produce on the back of the printing plate P, corresponding or complementary bosses or projections 15 so that when the printing plate is applied to the bed or plate support on the printing press, for the purpose of printing, these bosses or projections will fit into complementary sockets on such press support. Consequently the printing plate may be readily and instantly spotted or positioned on the press without the necessity of the tedious measurements commonly required 95 in the operation of what is usually known as registration. In other words, having determined where the printing plate is to be positioned on the press, the core plate E is properly adjusted in the casting operation, 100 as hereinafter described, to form bosses on the back of such printing plate in such position that the plate will fit on a predetermined field or portion of the plate support of the press. This general scheme of registration is described in my copending application Serial No. 98,917, filed May 20th, 1916.

By causing the lugs 10 on the clamping members to seat in certain of these sockets 11 of core plate, and which lug-receiving 110 sockets will, of course, lie nearer the edges of the core plate than those sockets of the latter which are to produce the bosses 15 on the printing plate, I insure that when the core plate is closed against the plastic material which forms the printing plate P, the matrix will not shift or move, and consequently an accurate molding of the plate and the bosses thereof may be had. Where a plurality of plates are to be made from 115 a plurality of matrices held in the casting box, as shown in Figs. 1, 2 and 7 the adjacent or confronting edges of the matrices are separated by walls or partitions W made up of clamping members similar to those 120 shown at C and D, these being placed back to back, or with their straight side walls in contacting relation as will be understood by reference to Fig. 7. Thus it will be noted that although a plurality of matrices are 130

placed upon the built-up bed of the casting box these matrices will be surrounded and clamped at all their edges by a suitable number of the clamping members. Further-
 5 more to insure the holding of the sectional casting box bed, the matrices, and the clamping members all in stationary and rigid position I may provide suitable outlying bearing and reinforcing bars 12 which are as-
 10 sembed to form a frame bearing against and embracing the rows of clamping mem- bers as will be understood by reference to Fig. 1. After these bars or bearers 12 have been so positioned, suitable furniture 13
 15 and quoins 14 are employed for securely locking all such assembled elements in the frame 1.

In order to mold the printing plate P, the material thereof which may be of any na-
 20 ture suitable for the purpose, such for in- stance as phenolic resin or phenolic condensa-
 tion product, is placed upon the matrix or matrices M in a sufficient quantity to sub-
 stantially come to the level of the top edges
 25 of the clamping members. The casting box bottom or bed is then placed upon the bot-
 tom platen F of a suitable press, as shown in Fig. 7. In said figure this press is simply conventionally illustrated, and also includes
 30 the top platen G which carries on its under-
 face the core plate E hereinbefore men-
 tioned. This core plate E as stated is pro-
 vided with sockets 11 which are intended to
 35 form the bosses 15 on the back of the plate P
 and in order to insure the proper location
 of the bosses on the plate so that the latter
 will register on the printing press support
 as hereinbefore mentioned, care should be
 40 taken to see that the lugs 10 of the clamping
 members of the casting box bed will seat in
 the proper or selected sockets of the core
 plate when the latter is lowered into plate-
 molding or pressing position. In order to
 45 limit the closing of the press I provide suit-
 able bearers 16 which rest upon the top
 face of the frame 1 of the casting box, and
 of course determines the degree of closing
 of the press and consequently the pressure
 to which the plastic mass is subjected in
 50 making the plate P.

In molding the plate from a phenolic con-
 densation product or a phenolic resin, which
 hardens and sets to an infusible form under
 heat and pressure, it is required of course,
 55 that the plastic mass be subjected to heating
 action and under such circumstances the
 press may be heated in any well known way.
 After the plastic material has been sub-
 jected to a sufficient degree of heat for the
 60 proper length of time to cause the harden-
 ing and setting of the plastic material, it
 may be cooled, either in the same press or
 through any convenient agency. However,
 I wish it to be understood that my invention
 65 is not limited in its useful application to

the casting of plates of phenolic material, as I have referred to the use of this substance simply by way of illustration.

After the plate P has been molded or cast as shown in Fig. 7 the platens of the 70 press may be opened and the core plate E which is preferably carried by the upper press platen G is thus withdrawn. The frame 1 with the bed B carrying the matrix and the plate may now be removed from the 75 press and the plate and matrix separated by simply lifting the former from off the face of the latter. Other casts or plates may then be made with the same matrix or series of matrices. In this connection it will be 80 seen by reference to Fig. 7 that the beveled faces of the clamping blocks or members will form correspondingly inwardly and down-
 85 wardly or under-edge bevels p on the print-
 ing plates, so that when the plate is reversed and positioned on the press these bevels will be inclined downwardly and outwardly and will constitute surfaces or sides which may be gripped and held by the well known plate clamps on the press. 90

In Fig. 8 I have shown one of the clamp-
 ing members C as provided with a spur or tongue 17 which forms an indication member adapted to seat in a registration 95 groove 18 formed on a non-type forming portion of the matrix, in the present instance one marginal edge of the latter. This tongue 17 when seated or centered in the indicating groove 18 will insure or indicate that the matrix is properly positioned be-
 100 neath a certain field or section of the core plate E so that the resulting plate molded from the matrix so positioned, will have its bosses formed on the back at predetermined points or centers, as is necessary for the 105 proper registration of the plate on the press, as hereinbefore described. If desired a sec-
 ond indicating groove 18' may be formed on an adjacent side of the matrix to receive a tongue similar to the tongue 17 but formed, 110 of course, on the clamping member which will lie against the bed in position to fit into such groove 18'.

In Fig. 9 I have shown a slightly modi-
 fied form of clamping device, in this case 115 the clamping members C' instead of having downwardly and inwardly beveled faces, are formed with vertical or straight faces 19 of relatively great depth, and in this case a backing block 20 of wood-fiber or other 120 suitable material, is molded or united with the back of the body of plastic plate mate-
 rial P' at the time of the making of the plate. Of course the plastic material will readily adhere to this block 20, under the ac-
 125 tion of heat and pressure, and when cooled will be found united therewith so that a plate completely backed up or mounted upon the block will result. Otherwise the struc-
 ture and operation of the arrangement 130

shown in Fig. 9 is the same as previously described for this sectional-bed casting box.

In Figs. 10 and 11 I have shown a modified form of bed for the casting box. In 5 this instance instead of making the bed of a series of assembled sections or blocks, and surrounding these blocks with clamping members, I provide a bed 21 which is preferably in the nature of a flat plate of steel 10 or other suitable material, with the top and bottom faces thereof machined and ground to insure accurate, flat, parallel surfaces. This bed plate 21 is bored to provide apertures or perforations 22 which are preferably arranged in rows, the apertures being spaced suitable distances apart. The purpose of these apertures is to provide sockets 15 for the reception of pins 23, depending from the clamping bars 24 and which bars may 20 be arranged to provide a clamping frame for the matrix which is shown at M'. It will be noted that the longitudinal edges of the bars are oppositely beveled as shown at 25 so that these beveled edges may overlap 25 the underlying marginal edges of the matrix and clamp the same in position while preventing the flow of any plastic plate material beneath the bars and consequently over 30 the edges of the matrix. This confinement 35 of the flow of the plastic material will obviate the possibility of the matrix sticking in the same as would be liable to occur were not this overlap of the clamp provided for as shown in Fig. 10. This same purpose is 40 accomplished in the structure illustrated in Figs. 1 to 9 previously described. Of course as will be understood by reference to Fig. 10, the clamping bars, being oppositely beveled at their longitudinal edges, may be reversed so that the matrix may be clamped by either longitudinal edge of the bar and furthermore the bars may be interchangeably placed on the field of the bed plate 21 or the positions of the bars may be changed 45 to suit the size and character of the particular plate being clamped.

Furthermore this bed plate 21 may be provided with suitable bearers 26 having pins 27 for seating in selected apertures 22 50 of the plate 21 the purpose of these bars of course being to limit the closure of the press and consequently the pressure to which the plastic material of the plate is to be subjected.

55 This form of casting box bed shown in Figs. 10 and 11 is exceedingly simple in its construction and possesses manifest advantages from the standpoint of convenience in operation and rigidity, being particularly 60 well adapted for the molding of single plates. In positioning the matrix M on this bed plate 21, a thin sheet of steel or other suitable material 28 of approximately the area of the matrix is placed on the bed and 65 the matrix then imposed thereon and sub-

sequently clamped in position by the clamping bars 24. The purpose of this thin sheet 28 of course is to prevent the material of the matrix from being forced under heat and pressure through such of the apertures 22 as 70 may lie directly beneath the same.

In Figs. 12 and 13 I have shown a still further modified form of casting box, in this instance the bed 29 of the box is provided with a clamp C² for clamping the matrix 75 M² and the core plate E' is mounted upon the top 30 of the casting box in such a manner as to be movable in two directions relative to the matrix, and consequently to the plate P² being made from the matrix. 80 These movements of the core plate E' relative to the top 30 may be attained in any suitable manner. In the present instance the top plate 30 carries a sliding bed plate 32 having a dovetailed tongue 33 working 85 in a corresponding dovetailed groove 34 so that this plate 32 may be shifted or slid back and forth in a single path relative to the top 30. For so shifting the plate 32 any suitable mechanism may be employed 90 such for instance as screw shaft 35, which is rotatable relative to the top but incapable of lengthwise movement of the same by reason of the key member 36 formed on the bottom face of the top and which seats in 95 the groove 37 formed near the end of the screw shank. The threaded section of the screw shank works in the bore 38, one-half section of which is unthreaded and is formed in the top 30, and the other half section of 100 which is threaded and is formed in the sliding plate 32. The result is that the plate 32 may be shifted back and forth relative to the top depending on the direction in which the screw is turned. The core plate E' itself 105 is adapted to slide or be shifted relative to this plate 32 or in a path transverse to the path in which plate 32 slides with the result that the core plate may be bodily shifted longitudinally and transversely. To shift 110 the core plate E' relative to the plate 32 I provide the top of such core plate with a dovetailed groove 40, which receives the dovetailed tongue 41 formed on the bottom face of the plate 32, while the screw 42, 115 similar to screw 35 is employed for shifting the core plate, the threaded section of the shank of the screw working in the bore 43, the upper unthreaded part of which is formed in the face of the plate 32 and the 120 lower threaded part of which is formed in the top face of the core plate. A small key member 44 extending from the bottom face of the plate 32 and projecting into the groove 45 formed near the end of the screw 125 tongue prevents a bodily longitudinal movement of the screw while permitting the latter to rotate. Thus by means of the two screws 35 and 42, the core plate may be shifted both longitudinally and laterally, 130

moving in one direction with the plate 32 and in another direction relative to the plate 32. Consequently the core plate may be moved up into one corner of the casting box, 5 or into abutting relation with the side walls 46 and 47 which are on the top 30 and form depending flanges therefor. The lower portions of these walls 46 and 47 are provided with open slots 48, and bolts 49 carried by the bottom or bed 29, project through these slots and are locked by means of the thumb nuts 50, as will be readily understood. Thus this form of casting box includes a bed and a flanged cover or top 15 carrying a core plate which may be adjusted, as is desired, to form bosses or indications in predetermined positions on the back of the plastic plate P^2 , for the purpose of press registration, as hereinbefore described. 20

In Fig. 14 I have illustrated a form of casting box which may be employed for the molding of curved plates. In said figure the numeral 51 indicates the base of the box 25 and this may be cored out in any suitable manner as shown at 52 to permit of the admission of either a heating agent or a cooling agent as may be deemed advisable, and as may be readily understood. For this 30 purpose steam or gas may be admitted to the base for heating purposes, or if desired, water may be fed thereto to act as a cooling agent. Upon this base I mount a semi-cylindrical or curved bed plate 53, the longitudinal flanges 54 of which rest upon the longitudinal side edges of the base 51. On this bed plate 53 I impose or position the matrix shown at M^3 , the matrix or plate, 35 possessing a degree of flexibility, may be curved or bent to conform to the semi-cylindrical shape of the bed plate, much in the manner that the ordinary stereotype matrix is bowed in making curved stereotype plates. The longitudinal side edges of 40 the matrix are confined or clamped in position by longitudinal clamping bars 55 fastened by screws or otherwise to strips or bars 56 imposed on top of the bed plate 54. These clamping bars 55 are shouldered as 45 shown at 57 so as to overlie and grip the adjacent edges of the matrix, the clamping bars being capable of being tightened against the edge of the matrix by screws which fasten such bar to the strip 56 as 50 shown at 57'. The matrix is confined at 55 both ends by suitable transverse curved strips such as are shown at 58, these strips being fastened by pins or the like shown at 59 to the bed plate 53. The matrix simply 60 abuts at its ends against these end strips 58, the latter being of sufficient depth to extend above the matrix the desired distance to accommodate the thickness of the plate to be cast. The plastic plate molding material 65 is shown at P^2 and in the operation of the

casting box is placed against the molding face of the matrix as is described for the making of flat plates. The core plate which is also of course semi-cylindrical in form is shown at 60 and is provided with the recesses 61 for forming the bosses 62 on the back of the plastic plate, the screws 63 being also provided for forming threaded bores in the back of the bosses to constitute means for enabling the bosses to be bolted to the 70 plate support on the printing press when the plate is in use. This core plate 60 is provided with flanges 64 which set on top of the bars 56 and hang or support the core plate in proper position. The core plate 80 may be heated or cooled in any suitable manner, and in the present instance the top platen or section 65 of the casting box is intended to be screwed or otherwise rigidly fastened to the top platen of the press (not 85 shown) a screw socket 66 being provided at each end of the platen for receiving the screw or fastening device by means of which the platen is so secured. The heating or cooling agent may be admitted in any suitable manner such for instance as through pipes or ducts conventionally indicated at 68. In other words this top plate 65 of the casting box being rigid with the top platen of press may be raised and lowered with the 90 latter, and will always be properly aligned with the base 51 of the box, and the latter, which rests upon the bottom platen of the press, may be rigidly secured to such platen in any desired manner, as by a bolt 69. In 100 Fig. 14 I have merely shown a portion of the frame or body of the upper platen of the press, the latter being indicated at 70 and is provided with suitable bolts and nuts, such for instance as indicated at 71, for the 105 purpose of properly securing and aligning the casting box platen 65 relative to this frame 70 of the press platen. Such a structure as is shown in Fig. 14 is of course intended to be used in the casting of partially 110 cylindrical or curved plates, and, outside of the necessary structural changes for making this particular shape of plate, operates on substantially the same principle as described for the flat plate casting box. 115

From the above description taken in connection with the accompanying drawings, it will be noted that I have provided certain forms of casting boxes wherein an article such as a printing plate, may be molded from a matrix in such manner as to not only accurately reproduce to the minutest detail the molding face or field of such matrix, but this may be accomplished without the liability of the plastic plate material 120 sticking to or embracing the edges of the matrix which would result in the inability to separate the plate and its matrix without damaging either or both. Furthermore, when used for the making of printing 125 130

6

plates, either curved or flat, it will be noted that through the agency of a core plate provided with indicating means corresponding to a field of similar indicating means on the 5 plate support of the printing press, that the plate may be molded or cast with certain designations, in the nature of bosses or other indications or marks which will enable the plate to be instantly spotted or 10 placed in a desired position of registration on the field of its support on the press.

While I have herein shown and described certain preferred embodiments of my invention, I wish it to be understood that I do 15 not confine myself to all the precise details of construction set forth by way of illustration, as modification and variation may be made without departing from the spirit of the invention or exceeding the scope of the 20 appended claims.

What I claim is:

1. In a casting box, a base member, a series of clamping members arranged end to end and surrounding the base members, 25 each of said clamping members having an inwardly projecting portion adapted to overlie and clamp a matrix on the base, and a core plate adapted to exert pressure against material positioned on the matrix 30 and to form indicating means on the material.

2. In a casting box, the combination with a base, and means for clamping the matrix thereon, a core plate associated with the 35 base and clamping means and adapted to form predetermined indications upon a body of material being molded upon the matrix, and means for adjusting the core plate to form such indications at predetermined points upon the material being molded.

3. In a casting box, a base frame, a base comprising a series of assembled blocks, clamping bars located at the sides of the base, each of said clamping bars having an 45 inwardly extending clamping flange adapted to overlie and clamp the edges of the matrix positioned on the base, retaining bars located in abutting relation to the outer faces of the clamping bars, and means 50 for locking the assembled base with the clamping bars and retaining the bars in the base frame.

4. In a casting box, a base frame, a base comprising a series of assembled blocks, 55 clamping bars adjustable on the base to vary the size of the casting box and each having an inwardly extending clamping flange adapted to overlie and clamp the edge of a matrix positioned on the base, retaining bars located in abutting relation to the outer faces of the clamping bars, and means for locking the assembled base, 60 clamping bars and retaining bars in the base frame.

5. In a casting box, a base frame, a base within the frame, clamping bars each having an inwardly extending clamping flange adapted to overlie and clamp the edge of a matrix positioned on the base and a section 70 projecting above the matrix to restrict the flow of material molded against the matrix, said bars being individually adjustable on the base to vary the size of the casting box, retaining bars located in abutting relation 75 to the outer faces of the clamping bars, and means for locking the assembled base, clamping bars and retaining bars in the base frame.

In testimony whereof I have hereunto set 80 my hand.

EMIL E. NOVOTNY.
